ROTARY REFINER

Edmund P. Arpin, Jr., Neenah, Wis.

Application February 25, 1948, Serial No. 10,625

9 Claims. (Cl. 92—26)

1

This invention relates to improvements in rotors for rotary machines which are used to refine wet, fibrous material, such as pulp, paper stock and the like.

In my copending applications for patent U. S. Serial No. 640,734, filed January 12, 1946, now Patent 2,475,869, and U. S. Serial No. 568,513, filed December 16, 1944, now Patent 2,451,708, I have described and claimed rotary refiners wherein a plurality of rotor refining elements are rotated within an abrasive lined cylindrical shell for coaction with the abrasive lining in the refining of fibrous material. The present application has to do with improvements in rotor construction and mounting for such refining machines.

Heretofore, rotors used in refining machines have been so constructed and arranged that replacement of the outer wearing portion necessitated the dismantling of the entire rotor assembly. A further disadvantage of rotors heretofore supplied in refining machines has been the tendency of the rotor stone to fracture under temperature variations due to the rigidity of the rotor mounting and to the many pressure concentration points on the stone caused by the mounting. The fact that the stone and the metal rotor housing have different expansion coefficients also tends to cause fractures in the stone.

In accordance with my present invention a plurality of rotor stones are each resiliently secured in a backing plate which is pivotally mounted in a housing attached to the rotating shaft of the refining machine. The resilient mounting exerts a constant compressive force which is applied against the stone through a pressure pad which extends between the mounting and the stone across substantially the entire width of the stone. The resilient mounting and the pressure distributing features of my invention greatly reduce the possibility of fracture of the stone during operation.

The mounting of the present invention is fastened to the stone at the outer marginal portion thereof adjacent the material processing surface. Thus, in refining machines employing a series of rotor assemblies positioned adjacent each other on the shaft of the machine, the stone of each rotor may be replaced without disturbing adjacent rotors. The time during which a machine is shut down for repair and maintenance is thus greatly decreased by the novel mounting of my invention.

It is therefore an object of the present invention to supply a mounting for a refining element in a rotor assembly which may be quickly and easily removed from or inserted into the backing

plate of the rotor assembly without disturbing adjacent rotor assemblies.

Another object of this invention is to provide a resilient mounting for the refining element of a rotor assembly.

A further object of this invention is to provide a mounting in which the pressures exerted by the clamping means are uniformly distributed over a large area of the refining element.

10 Other and further important objects, features and advantages of this invention will be apparent to one skilled in the art from the disclosures in the specification and the accompanying drawings.

On the drawings:

15 Figure 1 is a longitudinal elevational view of a rotary refiner embodying the principles of my invention, with parts broken away and in section, and with other parts in elevation;

Figure 2 is an enlarged vertical sectional view 20 taken substantially along the line II—II of Figure 1 with parts in elevation;

Figure 3 is an enlarged fragmentary elevational view of a rotor assembly disconnected from the refining machine.

25 Figure 4 is a plan view of a rotor assembly disconnected from the refining machine; and

Figure 5 is an end elevational view of a rotor assembly.

As shown on the drawings:

30 In Figure 1, the reference numeral 11 indicates generally a rotary refiner embodying the principles of my invention, including a generally cylindrical shell or casing 11 which is supported normally in horizontal position upon suitable supports 12. The shell 11 is provided with end plates 13 and 14, the end plate 13 at the inlet end of the machine having an inlet opening 15, and the plate 14 at the discharge end having a discharge opening 16. Each end plate is outwardly dished and provided with a central boss 18 defining a central opening for receiving, in bearing relation, a hollow shaft 19. Said shaft is adapted to be rotated centrally in the casing 11 by a grooved pulley 20. Disposed within the dished portion 35 of the inlet end plate 13 and secured to the shaft is an impeller member 21 which receives the material as it enters the inlet opening 15 and directs it toward its periphery for subsequent passage between the working surfaces of the refining machine.

40 The shell 11 is provided internally with a liner 22, composed of a number of ring sections 23 which are formed of suitable abrasive material, such as stone, metal or a synthetic ceramic of an abrasive type.

45 As best seen in Figure 2, a series of equi-spaced

helical grooves 24 extend longitudinally in the machine and form continuous passages along the inner surface of the ring sections 23.

The particular refining machine herein illustrated to disclose the novel rotor construction and mounting of the present invention includes rotor assemblies 25 mounted, in peripheral sets of four each, for rotation with the hollow shaft 19. Each rotor assembly includes a refining element 27 secured in a backing plate 28 which is pivotally mounted by a pin 30 on a box-like housing 29 keyed to the shaft 19. As the shaft 19 is rotated, the rotor moves outwardly by centrifugal force causing the refining element to coat with the abrasive surface of the liner ring 23 to refine the fibrous material as it is moved between the refining surfaces by the action of the impeller 21 and by the pressure head under which the material is delivered to the inlet opening.

A linkage 31 is associated with each rotor assembly to maintain a minimum clearance at all times between the surface of the refining element and the abrasive surface of the liner ring 23. This linkage, which is pivotally mounted to the backing plate 28 and to the box-like housing 29, has a push rod 33 pivoted from one end and extending through an opening in the hollow shaft 19. A series of wedge-like members 35 are disposed on telescoping rods 36 extending longitudinally inside the shaft 19. The position of each rod 36 in the shaft may be adjusted from the outside of the casing through an adjusting member 37. The inner end of each rod 33 is in contact with the face of one of the wedge-like members 35 and, thus, the position of the members 35 determines the extent of outward pivoting of the rotor assembly 25.

A leaf spring 39 is secured between the backing plate 28 and the linkage 31 to prevent the rotor elements from dropping away from the abrasive lining, as otherwise would occur in the case of the uppermost rotor element while the refiner is in motion.

Further details of construction and operation of a refining machine to which my novel rotor construction and mounting may be applied, may be had by reference to my copending application U. S. Serial No. 640,734, filed January 12, 1946, now Patent 2,475,869.

Referring to Figure 3, the backing plate 28 comprises a substantially flat central portion 37 having an upstanding bearing block 38 on which the linkage 31 is pivoted. At the trailing end of the backing plate, an overhanging ledge 40 extends across the plate forming a heel against which the corresponding portion of the stone 27 is pressed when the rotor is assembled.

At both sides of the plate 28 a wall portion 41 extends downwardly to provide a recessed chamber 42, Figure 5, which is adapted to receive, in guiding relation, a similarly formed strip 43 projecting upwardly on the stone 27.

An upstanding bearing block 44 is provided at each side of the leading end of the backing plate for receiving the pin 30 on which the rotor assembly is pivoted. Cut-out portions 45 are provided in the block 44 to receive, in countersunk position, the cotter pins or other securing means used to retain the pivot pin 30 in position.

A plurality of clamping members 51 are provided for holding the refining elements 27 in place against the backing plates 28. Each clamping member 51 comprises a bolt 55 mounted in a slanted passageway 56 in the rear portion of the backing plate 28. A coil spring 57 is disposed

on the bolt 55 between the head 58 of the bolt and a shoulder 59 provided in an enlarged upper end 60 of the passageway 56. In order to prevent rotation of the bolt during adjustment, a pin 64 is tightly positioned in a hole in the head 58 of the bolt. When the clamping member 51 is assembled, the pin 64 is disposed in a slot 63 cut across the backing plate 28. In an alternate form, a drilled hole may replace the slot 63.

A nut 65 is threaded on the lower end of the bolt against a rocker member 66 which is loosely disposed on the bolt with its arm portions extending outwardly. One rounded arm portion 67 is seated in a segmental spherical socket 68 formed in a pressure pad 69 while the other arm is arranged to seat in a socket 70 of the backing plate 28. The pressure pad 69 extends across the refining element 27 and uniformly distributes the pressure exerted by the clamping means.

It is therefore evident that tightening of the nut 65 on the bolt 55 causes the rocker member to pivot in the recess 70, pressing the arm 67 against the pressure pad 69. Thus, a compressive force is applied to the refining element 27 causing it to be firmly pressed upwardly in the recessed chamber 42 and forwardly against the heel 40 of the backing plate 28.

The surfaces of the refining element 27 that are in contact with the backing plate 28 and the pressure pad 69 will ordinarily be smooth and accurate. However, a cushioning material 73, such as rubber, soft metal alloy or plastic may be positioned between the surfaces.

It is to be understood that as many clamping members may be used as is required by the size of the rotor assembly.

A cotter pin 71 is secured in the threaded end of the bolt 53 to prevent the nut from working loose from the bolt during operation of the refining machine. A cap screw 72 passes freely through an opening in the arm 67 and is threaded into the pressure pad 69. The head of the cap screw 72 is spaced from the arm 67 when the arm is in locked position against the pressure pad 69. Thus, the cap screw 72 loosely secures the pressure pad to the arm 67 and, when the clamping members are loosened, the pressure pad will be prevented from falling loose from the assembly.

To facilitate the removal of the refining element 27 from the backing plate 28, there is provided a tapped hole 75 in the heel 40 of the plate. By threading a stud into this hole when the clamping elements have been removed from the assembly, the refining element may be quickly and easily forced out of position in the rotor assembly.

From the foregoing description it is seen that there is provided in this invention a resilient, adjustable mounting for a refining element in a rotor assembly.

This resilient mounting will automatically absorb shocks due to changes in temperature and other variable operating conditions. It is also seen that, by providing the clamping means at the outer marginal portion of the rotor assembly each refining element may be removed from or inserted into the backing plate without disturbing the adjacent rotor assemblies in the refining machine.

Further, the pressure pad which extends across the width of the refining element provides means for uniformly distributing the pressure exerted by the clamping means on the refining element.

It will, of course, be understood that various details of construction may be varied through a

wide range without departing from the principles of this invention, and it is, therefore, not the purpose to limit the patent granted hereon otherwise than necessitated by the scope of the appended claims.

I claim as my invention:

1. In a rotary refiner, a rotor assembly comprising a metal backing plate, a stone refining element positioned in said backing plate, and means including a spring-pressed rocker arm pivotally mounted on said backing plate for holding said element in said backing plate, said means serving to distribute more evenly the retaining pressure against said stone refining element.

2. In a rotary refiner, a rotor assembly comprising a backing plate, a refining element positioned in said backing plate, and means including a spring-pressed rocker arm and a pressure pad spaced from said backing plate and between said element and said rocker arm for holding said element in said backing plate.

3. In a rotary refiner, a rotor assembly comprising a metal backing plate, a stone refining element secured in said backing plate, and lever means operable on the outer marginal portion of said element for adjusting said element in said backing plate, said lever means including a pad to distribute more evenly the retaining pressure against said stone refining element.

4. In a rotary refiner including a plurality of rotors assembled adjacent each other on a common shaft, a metal rotor assembly comprising a backing plate, a stone refining element positioned in said backing plate, and adjustable means associated with the outer marginal surface of said backing plate and said refining element for adjusting the position of said element in said backing plate without disassembling the adjacent rotor assembly, said means serving to distribute more evenly the retaining pressure against said stone refining element.

5. In a rotary refiner, a rotor assembly comprising a metal backing plate, a stone refining element positioned in said backing plate, and an adjustable spring-pressed rocker arm pivoted at one end on the outer surface of said backing plate and at the other end on the outer surface of said refining element for urging said refining element into position on said backing plate, said rocker arm having at its end adjacent the outer surface of the refining element a pad serving to distribute more evenly the retaining pressure against said stone refining element.

6. In a rotary refiner, a rotor assembly comprising a metal backing plate, a stone refining element positioned in said backing plate, resilient cushioning means disposed between said backing plate and said element and spring loaded means for holding said element in said backing plate, said resilient cushioning means and said spring-loaded means coacting to distribute more evenly the retaining pressure against said stone refining element.

7. In a rotary refiner, a rotor assembly comprising a backing plate having a recessed portion with walls on three sides thereof, a refining element positioned in said recessed portion of said backing plate, a cushioning pad in said recessed portion between said refining element and said backing plate and spring-pressed lever means operable on said element for adjustably holding said element in said recessed portion, said cushioning pad and said spring-pressed lever means coacting to distribute more evenly the retaining pressure against said refining element.

8. In a rotary refiner, a rotor assembly comprising a backing plate including a recessed portion defined by overhanging flanges, slanted passageways near the leading edge of said rotor assembly, and upstanding bearing portions for connection to the drive mechanism of the refiner, a refining element movable into said recessed portion against said overhanging flanges having a generally arcuate processing surface and a flat portion extending across the leading edge, a pressure pad positioned on said flat portion, and spring-pressed clamping means disposed in the slanted passageways of said backing plate having a rocker member pivoted at one end on said backing plate and bearing at the other end against said pressure pad for pressing said element into the recessed portion of said backing plate.

9. In a rotary refiner, a rotor assembly comprising a metal backing plate having a recessed portion defined on three sides by overhanging flanges, and having, near the leading edge of the plate, an indented socket portion and a plurality of slanted passageways, a stone refining element movable into the recessed portion of the backing plate, a pressure pad associated with the leading edge of said refining element and having a spherical socket on one surface thereof, cushioning material between said refining element and said backing plate and between said pressure pad and said refining element, and clamping means including a rocker arm pivoted at one end in the socket portion of said backing plate and engaging at the other end the spherical socket portion of said pressure pad, said cushioning material and said pressure pad coacting to distribute more evenly the retaining pressure against said stone refining element.
